Primary Examiner — Dominic V Simone(74) *Attorney, Agent, or Firm* — Banner & Witcoff, Ltd.(57) **CLAIM**

The ornamental design for a shoe upper, as shown and described.

DESCRIPTION

FIG. 1 is a front perspective view of a shoe upper showing my new design;

FIG. 2 is a front view thereof;

FIG. 3 is a top view thereof;

FIG. 4 is an enlarged view of FIG. 3 with unclaimed subject matter omitted thereof;

FIG. 5 is a front perspective view of the shoe upper in FIGS. 1-3 shown in an alternate configuration;

FIG. 6 is a front view thereof;

FIG. 7 is a top view thereof; and,

FIG. 8 is an enlarged view of FIG. 7 with unclaimed subject matter omitted thereof.

The broken lines immediately adjacent to the shaded area define the bounds of the claimed design and form no part thereof. The broken lines showing the remainder of the shoe represent unclaimed subject matter and form no part of the claimed design.
